[57] CLAIM

The ornamental design for a bathing enclosure, as shown and described.

DESCRIPTION

FIG. 1 is a perspective view taken from the top, front and right side of a bathing enclosure embodying my new design;

FIG. 2 is a front elevational view thereof;

FIG. 3 is a top perspective view thereof;

FIG. 4 is a right side elevational view thereof;
FIG. 5 is a cross-sectional view taken on line 5—5 of FIG. 2;

FIG. 6 is a cross-sectional view taken on line 6—6 of FIG. 3;

FIG. 7 is a left side elevational view thereof;

FIG. 8 is a perspective view taken from the top, front and right side of a second embodiment of my new design;

FIG. 9 is a front elevational view of the embodiment of FIG. 8;

FIG. 10 is a top perspective view thereof;

FIG. 11 is a right side elevational view thereof;

FIG. 12 is a cross-sectional view taken on line 12—12 of FIG. 9;

FIG. 13 is a cross-sectional view taken on line 13—13 of FIG. 10; and,

FIG. 14 is a left side elevational view thereof.

The fragmentary broken line representations of a wall and a floor in FIGS. 1 and 8 and of a grab bar in FIGS. 1, 2, 3, 6, 8, 9, 10 and 13 are for the purpose of illustration only and form no part of the claimed design.
